UNITED STATES PATENT OFFICE

FRANK A. BULLINGTON, OF KANSAS CITY, MISSOURI, ASSIGNOR TO BULLINGTON ENGINE HEADS, OF KANSAS CITY, MISSOURI, A COMMON-LAW TRUST CONSISTING OF HENRY C. TAMMEN, HOWARD P. TREADWAY, AND FRANK A. BULLINGTON

ANTIDETONATING COMBUSTION-CHAMBER CYLINDER HEAD

Application filed November 12, 1928. Serial No. 318,966.

My invention relates to internal combustion engines and more particularly to such engines having cylinder heads provided with anti-detonating combustion chambers.

It is a purpose of my invention to provide a cylinder head with a combustion chamber of the above mentioned character by providing space in said cylinder head in the form of a chamber or recess adjacent the spark plug for absorbing the compression wave following ignition of the charge adjacent the spark plug. It is also a purpose of my invention to provide means associated with a combustion chamber of the above mentioned character extending over the end of the cylinder for distributing initial combustion pressure substantially uniformly over the head of the piston operating in said cylinder at the time of initial combustion, said means being so arranged as to subdivide the terminal combustion and to diffuse the pressure wave of said terminal combustion to thereby prevent the occurrence of detonation. A form of such means is shown in my copending application Serial #318,965 filed November 12, 1928, there being, however, certain difference in structure and function in the combustion chamber and distributing means shown in this application that have certain advantages and are improvements over the construction shown in said above mentioned copending application. By terminal combustion is meant the burning of the last portion of the fuel charge, which is usually that portion most remotely located with relation to the spark plug, or that portion of the fuel charge which is considerably diluted with inert gas remaining in the combustion chamber after a preceding explosion, and detonating combustion as commonly encountered in high compression engines, particularly when employing ordinary gasoline for fuel, is commonly associated with said terminal combustion.

The means for preventing detonation incorporated in this application are different in form and arrangement and introduce certain new principles and improved features over what is shown in said copending application, one of said features being the pro-

vision of a combustion chamber including means of an annular form for the relative isolation or retention of a portion of the inert burned gas during the suction stroke of the piston, said means being in the form of an annular recess forming a portion of the combustion space. The annular pocket or recess is formed preferably substantially concentric, relative to the spark plug, and is arranged to extend over the valves and to overlap the end of the cylinder at one side thereof. Preferably, and in the arrangement shown in the drawing, said annular chamber or pocket is formed so as to extend in an inclined or sloping manner in relation to the axis of the cylinder, so that the valve pocket combustion chamber of the engine will have a greater capacity in that portion thereof which overlaps the end of the cylinder and a smaller capacity for that portion thereof overlying the valves.

By providing the annular form for the groove or pocket forming the cushioning chamber the spark terminals of the ignition means may be so located, and are preferably so located, as to lie substantially at the geometrical center of the chamber formed by said annular groove or pocket, whereby the distance for fuel travel from the ignition means to the extremities of the combustion chamber in the cylinder head will be substantially equal in all directions.

In operation, the fresh fuel enters through the inlet port, will pass into the cylinder with a minimum amount of mingling with the inert gas contained in the annular portion of the combustion chamber overlying the cylinder, said inert gas in this portion of the chamber being then subject to the cooling effect of the cooling medium provided around the surrounding wall portion of said annular pocket or chamber. The comparative isolation and cooling of the inert gas during the intake stroke of the piston, during which fresh fuel is drawn into the cylinder, will effect greater volumetric efficiency for the engine. The annular form of the groove and the particular cross sectional shape of the annulus will be particularly effective in this respect, and it will be noted, upon re-

ferring to the drawings, that the area of the wall in contact with the gas in the annular pocket or recess is relatively large in proportion to its cross sectional area, particularly at the inner portion thereof, or the portion more remote from the opening leading into the same from the remainder of the combustion chamber. During compression the fuel will be displaced from the cylinder into the annular portion of the combustion chamber in a manner to cause turbulence and thoroughly mix the fresh fuel mixture and the residual inert burned gas in said annular portion of the combustion chamber.

15 A purpose of my invention, in providing the annular form of recess or pocket in a combustion chamber, is to provide such a combustion chamber that any differential in the richness of compressed fuel charge contained in said combustion chamber at the time of ignition will occur in such a manner that the leaner portion of the charge will be contained in the annular portion of the combustion chamber and more particularly in that portion of the annular recess most remote from the spark plug. As the annular recess is formed so that the annular cross section thereof diminishes in a direction toward the closed inner end wall thereof, the terminal portion of the charge contained therein, or that portion most remote from the ignition means lying adjacent the closed inner end wall of the annular recess, will be of a relatively small section with a relatively large wall area adjacent thereto. With the condition of fuel mixture referred to above, terminal combustion will occur in this small section of the annulus, the fuel content of which is distributed over a relatively large circumferential distance and will be substantially equidistant from the point of initial ignition of the fuel charge, whereby no relatively large mass of fuel mixture is subject to terminal combustion and the associated tendency toward detonation.

40 Thus the annular portion of the combustion chamber comprises means for distributing terminal combustion, for cooling the fuel mixture in which terminal combustion occurs, and anti-detonation means for said combustion chamber.

45 While the pressure distributing means over the cylinder head referred to above, is particularly effective to distribute the initial combustion pressure to that portion of the cylinder most remote from the valve pocket combustion chamber, and to divide the terminal combustion pressure wave into components, it is a purpose of my present invention

50 to utilize the pressure distributing means during the compression stroke, and particularly toward the end of said stroke, to effect turbulence in the combustion chamber, said means being so formed as to cause a cross stream of fuel to be directed in said combus-

tion chamber toward the spark plug terminals.

70 The pressure distributing means preferably comprises a substantially centrally located transverse supply channel and means associated therewith extending over the portion of the cylinder most remote from the valve pocket chamber so as to distribute initial combustion pressure substantially uniformly over the portion of the head of the piston most remote from the valve pocket chamber and so arranged as to divide the terminal combustion pressure wave into components acting in a direction away from each other. Said distributing means preferably comprises grooves extending in divergent relation from the central supply channel so as to direct the flow of pressure, and particularly the above mentioned divisions of the terminal combustion wave, away from each other. The central supply channel and the grooves referred to, preferably, radiate from substantially the axial center of the cylinder and the grooves so distribute combustion pressure over the half of the piston head most remote from the valve chamber that a substantially balanced application of explosion pressure to the piston results.

75 The pressure distributing means is preferably constructed so as to decrease in cross sectional area away from the valve pocket chamber, the progressively decreasing cross sectional area of the grooves toward the extremities thereof is provided to progressively diminish the fuel content of the grooves as combustion progresses toward the extremities thereof to effect terminal combustion in a minimum quantity of charge. Furthermore, the walls of said grooves serve as cooling means for the portion of the charge therein, being particularly effective for this purpose at the shallow ends thereof. Said grooves thus serve as terminal combustion cooling and diffusing means constituting a means to effect anti-detonation operation for a high compression engine. Such combustion pressure distributing means is shown in a broad sense in my application, Serial #249,892, filed January 27, 1928, and the distributing means in the present invention, constitutes a 80 improvement over the distributing means shown in said above referred to application.

85 Other objects and advantages of the invention will appear as the description of the drawings proceeds. I desire to have it understood, however, that I do not intend to limit myself to the details of structure shown or described, but that I intend to include as part of my invention, all such obvious changes and modifications as would occur to a person skilled in this art and as would fall within the scope of the claims.

cylinder block adjoining the same, the lower portion of the cylinder block being broken away, said section being taken substantially on the line corresponding to line 1—1 of Fig. 2.

Fig. 2 is a fragmentary bottom plan view of the cylinder head, the position of the valves and the cylinder relative thereto, when the cylinder head is in position, being shown diagrammatically in dotted lines thereon.

Fig. 3 is a section taken on the line 3—3 of Fig. 1 looking in the direction of the arrows, the spark plug being omitted, and

Fig. 4 is a view similar to Fig. 1 of a modification.

Referring in detail to the drawings, my improved cylinder head is shown as being applied to a cylinder block having a cylinder 10 in which the piston 11 operates in the usual manner. The cylinder is shown as being provided with a space 12 for cooling medium and the inlet and exhaust valves are mounted in said cylinder block, said valves being shown diagrammatically in Fig. 2, the inlet valve 13 being also shown in Fig. 1, the exhaust valve 14 being similar to the valve 13 and being shown only in Fig. 2. The valve 13 controls communication between the engine cylinder 10 and the intake passage 15.

Associated with said cylinder block is a cylinder head 16, which is provided with the space 17 for cooling medium and which is further provided with a valve pocket combustion chamber 18. The combustion chamber 18 overlaps the cylinder at 19, at one side thereof and is provided with an annular grooved portion 20 forming an annular pocket or recess in the combustion chamber 18. The groove 20 is so arranged that the axial center line thereof is inclined at an oblique angle to the longitudinal axis of the cylinder 10, the said center line being inclined away from the cylinder axis, whereby the portion of the groove 20 overlapping the cylinder is spaced at a greater distance from the top face of the cylinder block than that portion of the groove 20 adjacent the wall 21 of the valve pocket combustion chamber most remote from the cylinder, the combustion chamber having an annular portion gradually decreasing in depth from the portion of said groove over the cylinder around the same in opposite directions to the portion thereof most remote from the cylinder. By this arrangement the greatest portion of the combustion space in the combustion chamber 18 is in that portion of the same adjacent the cylinder 10 and the smallest portion thereof is adjacent the wall 21 and over the valves.

The valve pocket combustion chamber is provided with suitable ignition means 22 shown as being in the form of a spark plug mounted in the threaded opening 23 provided in the cylinder head therefor, said opening

being coaxial with the annular groove 20, whereby the spark plug terminals 24 are located substantially on the axial center line of the said annular groove, said terminals being located in the valve pocket combustion chamber 18 near the opening of the valve pocket combustion chamber into the cylinder.

The cylinder head is provided with a restricting flat wall portion 25 overlying the cylinder and having mechanical clearance 75 from the head portion 26 of the piston 11, when the same is at the end of its compression stroke, the restricting flat wall portion serving to restrict the application of initial combustion pressure to the piston head. The restricting wall portion 26 is shown as being in substantial alignment with the flat face 27 on the cylinder head cooperating with the flat face 28 on the cylinder block to clamp the gasket 29 therebetween.

The annular groove 20 is provided with a closed inner annular end wall 30 and the groove gradually decreases in width from the opening leading into the chamber 18 from said groove to said closed end wall 30. Said groove is further provided with an outer annular wall portion 31 that extends substantially parallel to the axis of the cylinder 10, and with a sloping inner annular wall portion 32 curving gradually to the substantially flat wall portion 33 in which the spark plug 22 is mounted.

The groove 20 thus extends around the spark plug and is concentric therewith and corresponding portions of the groove at any point therein are located equidistantly from the ignition means, the most remote portions of the groove adjacent the end wall 30 being, consequently, spaced the same distance from the ignition means all the way around the same. This provides the spreading over a large area in a thin layer of the portion of the charge in which terminal combustion occurs.

The groove 20 will contain inert hot gas when the intake stroke of the piston 11 begins, and the incoming fresh fuel mixture will not mingle to any extent with the contents of that portion of the groove overlying the cylinder but will pass by the same into the cylinder 10. Thus the inert hot burned gas is isolated therein from the fresh fuel charge and the inert gas in this portion of the groove is cooled due to being in contact with a relatively large cooling surface provided by the walls of the groove, whereby the thermal efficiency of the engine is increased. When the compression stroke of the piston takes place turbulence is set up in the groove and the inert gas therein is mixed with the fresh fuel mixture entering the same, displacing some of the inert gas from the groove into the remainder of the combustion chamber where it mingles with the fuel mixture therein. Thus a combustible mixture is provided in the valve pocket com-

- bustion chamber, and in the annular groove therein, but the proportion of inert gas in the mixture in the annular groove is greater than in the mixture in the main portion of the 5 valve pocket combustion chamber thus providing a leaner, slower burning combustible mixture in the annular groove or recess than in the main portion of the valve pocket combustion chamber.
- 10 In addition to the annular pocket or recess 20 serving as a combustion pressure cushioning and explosion wave absorbing chamber, combustion pressure distributing and explosion wave diffusing means is provided in 15 the flat restricting wall portion 25 of the cylinder head. Said means comprises a supply passage 34 extending from the valve pocket chamber 18 and distributing grooves 35 leading from said supply passage. The supply 20 passage 34 is preferably centrally arranged and the grooves 35 diverge therefrom, and in the embodiment shown the passage 34 extends substantially on the transverse diameter of the cylinder from the valve pocket 25 chamber 18 to a point substantially over the axial center of the cylinder and the grooves 35 diverge symmetrically therefrom and extend substantially radially from near the axis of the cylinder.
- 30 It will be noted that the passage 34 decreases in depth away from the valve pocket chamber and that the grooves 35 decrease in depth from the central point of supply from the passage 34 to the extremities 36 thereof.
- 35 Said extremities are rounded as will be evident from Fig. 2 and lie substantially in alignment with the wall of the cylinder 10, said extremities having the walls thereof curved in all directions, as will be evident 40 from Figs. 1, 2 and 3.
- The passage 34 constitutes a restricted opening from the valve pocket chamber into the pressure distributing grooves, thus causing a differential in the pressure to exist between the valve pocket chamber 18 and 45 grooves 35 when initial combustion takes place. The walls 37 at the entrance to the groove 34 are rounded to provide for the more ready passage of some of the contents 50 of valve pocket chamber 18 into said passage 34.
- Due to the provision of the inclined inner end wall 38 of the passage 34, the fresh fuel mixture in the cylinder will, during the compression stroke, and particularly near the end 55 thereof, be directed toward the ignition terminals 24 and transversely across the annular groove 20 to provide a cross current of fresh fuel mixture across the chamber 18 to create 60 turbulence therein.
- The arrangement of the grooves 35 will serve to provide a substantially uniform distribution of initial combustion pressure over the half of the piston head 26 remote from 65 the valve chamber and under the restricting

wall portion 25 and also provides for the diffusion of terminal combustion pressure and the directing of the terminal combustion pressure waves away from each other.

In Fig. 4 a somewhat modified form of cylinder head is shown for use on a relatively short stroke engine, particularly when high compression is employed, in which case the combustion chamber is of necessity relatively small. The construction of the cylinder head is substantially the same as previously described, except for the formation of the annular grooved portion of the valve pocket chamber and the proportions of the combustion chamber itself.

The parts that are substantially the same in Fig. 4 as in Figs. 1 to 3, inclusive, are indicated by the same numerals in Fig. 4 as in said figures. The principal difference between the cylinder head 16' shown in Fig. 4 and the head 16 shown in Figs. 1 to 3, inclusive, is that the major portion of the inner wall portion or ceiling of the chamber 18' is relatively flat, that is the flat wall portion 33' in Fig. 4 is much larger and placed more nearly adjacent the face of the piston than in the form shown in Figs. 1 to 3 and said wall portion 33' also is arranged more closely to the cylinder block to reduce the size of the valve pocket chamber. The annular groove 20' is made of decreasing depth from the portion thereof in alignment with the transverse diameter of the cylinder, and overlying said cylinder, to the portion of the valve pocket chamber most remote from the cylinder. Due to the provision of the annular groove, the wall portion 33' can be placed much nearer the top face of the cylinder block than would be otherwise possible as the annular groove 20' will be of such size as to provide sufficient capacity for the unobstructed flow of the gases to and from the cylinder. The annular groove is made of a relatively small capacity in this form of the invention and the groove 20' is arranged to lie with its axis at a much smaller angle to the axis of the cylinder than in the form shown in Figs. 1 to 3, inclusive, but is inclined sufficiently to place the portion of the valve pocket chamber of relatively greater capacity overlapping the cylinder. 110 The groove 20' is of similar shape in cross section to the groove 20, tapering toward the wall portion 30' thereof, but decreasing in depth from that portion thereof over the cylinder to the portion remote from the cylinder. It will be obvious that the inclination of the annular groove 20' may be varied as desired to obtain the desired form and size of combustion chamber in the cylinder head. 115 The action and purpose of the annular groove or recess is substantially the same in both forms of the invention.

Having thus described my invention, what I desire to claim and secure by United States Letters Patent is:

1. In an internal combustion engine, a cylinder, and a cylinder head having a valve pocket combustion chamber therein at one side thereof, overlapping said cylinder, valves in said valve pocket chamber, said valve pocket chamber having an annular recess therein extending over said cylinder and over said valves, said chamber being relatively deep over said cylinder and relatively shallow over said valves. 70
2. A cylinder head of the character described, having a valve pocket recess therein provided with an annular chambered portion, said annular chambered portion gradually decreasing in depth from a relatively deep portion thereof at one side of said recess to a relatively shallow portion at the opposite side of said recess. 75
3. A cylinder head of the character described, having a valve pocket recess therein provided with an annular groove portion, and combustion pressure distributing means extending from said recess in said cylinder head comprising diverging grooves remote from said recess. 80
4. In an internal combustion engine, a cylinder and a cylinder head having a valve pocket combustion chamber therein and having a restricting wall portion overlying said cylinder, said head having combustion pressure distributing means overlying said cylinder, said means comprising diverging grooves in that portion of said restricting wall portion overlying the portion of the cylinder remote from the valve pocket chamber, said grooves decreasing in cross sectional area toward the divergent extremities thereof. 85
5. In an internal combustion engine, a cylinder and a cylinder head having a valve pocket combustion chamber therein, and having combustion pressure distributing means overlying said cylinder, said means comprising diverging grooves overlying that portion of the cylinder remote from the valve pocket chamber and a groove extending from said valve pocket chamber to said diverging grooves and opening into the same. 90
6. In an internal combustion engine, a cylinder and a cylinder head having a valve pocket combustion chamber therein, and having combustion pressure distributing means overlying said cylinder, said means comprising diverging grooves overlying that portion of the cylinder remote from the valve pocket chamber and a substantially centrally arranged groove extending from said valve pocket chamber to said diverging grooves and opening into the same. 100
7. In an internal combustion engine, a cylinder and a cylinder head having a valve pocket combustion chamber therein, and having combustion pressure distributing means overlying said cylinder, said means comprising diverging grooves overlying that portion of the cylinder remote from the valve pocket chamber and a groove extending from said valve pocket chamber to said diverging grooves and opening into the same, said portion of the cylinder remote from the valve pocket chamber and a groove extending from said valve pocket chamber to said diverging grooves and opening into the same, said groove having combustion pressure distributing means overlying said cylinder, said means comprising diverging grooves in said groove. 105
8. In an internal combustion engine, a cylinder and a cylinder head having a valve pocket combustion chamber therein, and having combustion pressure distributing means overlying said cylinder, said means comprising diverging grooves overlying that portion of the cylinder remote from the valve pocket chamber and a connecting groove extending from said valve pocket chamber to said diverging grooves and opening into the same, said grooves diverging substantially symmetrically away from said connecting groove. 110
9. In an internal combustion engine, a cylinder and a cylinder head having a valve pocket combustion chamber therein, said valve pocket chamber having an annular recess therein, and said cylinder head having combustion pressure distributing means overlying said cylinder, said means comprising diverging grooves overlying that portion of the cylinder remote from the valve pocket chamber. 115
10. In an internal combustion engine, a cylinder and a cylinder head having a valve pocket combustion chamber therein, said valve pocket chamber having an annular groove therein, and said cylinder head having a grooved restricting wall portion overlying said cylinder. 120
11. In an internal combustion engine, a cylinder, valves at one side of said cylinder, and a cylinder head having a valve pocket combustion chamber therein overlapping one side of said cylinder, said valve pocket chamber having an annular recess therein defining a projecting wall portion in said head surrounded by said recess, said recess extending over said valves and said cylinder. 125
12. In an internal combustion engine, a cylinder, valves at one side of said cylinder, a cylinder head, and ignition means in said cylinder head, said cylinder head having a combustion chamber therein overlying said valves and overlapping one side of said cylinder, said chamber having an annular recess therein defining a projecting wall portion in said head in which said ignition means is mounted surrounded by said recess. 130
13. In an internal combustion engine, a cylinder and a cylinder head having a valve pocket combustion chamber therein, and a restricting wall portion in said head overlying the cylinder, said restricting wall portion having combustion pressure distributing means overlying said cylinder, said means comprising diverging grooves in said restricting wall portion overlying that portion of the cylinder remote from the valve pocket chamber and a groove extending from said valve pocket chamber to said diverging grooves and opening into the same, said groove having combustion pressure distributing means overlying said cylinder, said means comprising diverging grooves in said groove. 135

tion of the cylinder remote from the valve pocket chamber.

14. In an internal combustion engine, a cylinder, a cylinder head, valves at one side of said cylinder, and ignition means in said cylinder head, said cylinder head having a combustion chamber therein having an annular groove extending over said valves and around said ignition means, the transverse section of said groove decreasing in width toward the bottom thereof.

15. In an internal combustion engine, a cylinder, a cylinder head, valves at one side of said cylinder, and ignition means in said cylinder head, said cylinder head having a combustion chamber therein, having an annular recess therein defining a projection surrounded by said recess, said recess extending over said valves and gradually narrowing from the annular opening of said recess into the remainder of the combustion chamber to the closed annular end wall thereof.

In testimony whereof, I hereunto subscribe my name this 8th day of November, 1928.

FRANK A. BULLINGTON.
